DESIGN FOR A TRACTOR HITCH

Raymond F. Gieszl, Vicksburg, Miss., assignor to
R. G. Le Tourneau, Inc., Stockton, Calif., a cor-
poration of California

Application October 21, 1942, Serial No. 108,587

Term of patent 14 years

To all whom it may concern:

Be it known that I, Raymond F. Gieszl, a citizen of the United States, residing at Vicksburg, in the county of Warren and State of Mississippi, have invented a certain new, original, and ornamental Design for a Tractor Hitch, of which the following is a specification, reference being had to the accompanying drawing, forming a part thereof.

In the drawing:
Figure 1 is a side elevational view of a tractor hitch, showing my new design; and
Figure 2 is a top plan view of the same.

I claim:
The ornamental design for a tractor hitch, as shown.

RAYMOND F. GIESZL.
